FLUID BLAST CIRCUIT INTERRUPTER

Winthrop M. Leeds, Pittsburgh, Pa., assignor to
Westinghouse Electric Corporation, East Pittsburgh, Pa., a corporation of Pennsylvania

Application January 1, 1945, Serial No. 570,820

19 Claims. (Cl. 200—150)

1

This invention relates to circuit interrupters in general, and, more particularly, to arc-extinguishing structures therefor.

In United States patent application, filed September 14, 1944, Serial No. 553,997, by Winthrop M. Leeds and assigned to the assignee of the instant application is shown and claimed a novel operating mechanism for a circuit interrupter. It is an object of my invention to provide an improved arc-extinguishing structure of the type described in the aforesaid application.

A general object of my invention is to provide an improved circuit interrupter which will more effectively interrupt the circuit therethrough in a novel manner.

More specifically, it is an object of my invention to provide an improved arc-extinguishing unit in which a bridging member adapted for rotation electrically connects two relatively stationary contacts. A plurality of inlet passages and vent passages communicate with an interrupting passage in which an interrupting arc is established by the separation between the bridging contact and one of the relatively stationary contacts. Preferably, the separation between the bridging contact and the other contact establishes a pressure-generating arc to force fluid through the inlet passages toward the interrupting arc to effect extinction thereof.

Further objects and advantages will readily become apparent upon a reading of the following specification taken in conjunction with the drawings, in which:

Figure 1 is an elevational view partly in section of a circuit interrupter embodying my invention and shown in the open circuit position;

Fig. 2 is an enlarged elevational view of the right-hand arc-extinguishing assemblage of Fig. 1 with a vertical sectional view taken through the upper arc-extinguishing unit substantially on the line II—II of Fig. 3, the parts being shown in the full open circuit position;

Fig. 3 is a sectional view taken along the line III—III of Fig. 2;

Figs. 4 and 5 show plate details used in the construction of the arc-extinguishing unit shown in section in Fig. 2;

Fig. 6 is an elevational view of a modified type of arc-extinguishing assemblage, the upper modified arc-extinguishing unit being shown in vertical section taken substantially along the line VI—VI of Fig. 7, the parts being shown in the full open circuit position;

Fig. 7 is a sectional view taken along the line VII—VII of Fig. 6;

2

Figs. 8 and 9 show plate details used in the construction of the modified type of arc-extinguishing unit shown in Fig. 6; and

Fig. 10 is a vertical sectional view taken along the line X—X of Fig. 6.

Referring to the drawings and, more particularly, to Fig. 1 thereof, the reference numeral 1 designates a tank in which a suitable arc-extinguishing fluid 2, in this instance circuit breaker oil, is filled to the level 3. Depending from the cover 4 of the tank 1 are two insulating bushings 5, 6 through which extend terminal studs 7, 8. To the lower ends of the terminal studs 7, 8 are threadedly secured contact feet 9, 10 which fixedly support in position two identical arc-extinguishing assemblages generally designated by the reference numeral 11.

Each arc-extinguishing assemblage 11 comprises a plurality of, in this instance two, arc-extinguishing units generally designated by the reference numeral 12. Electrically interconnecting the two arc-extinguishing assemblages 11 is a movable conducting bridging member 13 which is reciprocably operated in a vertical direction by an insulating rod 14 actuated by suitable mechanism, not shown.

The upward or closing movement of the bridging member 13 causes the ends 15 thereof to slide through disconnect fingers 16 striking cross-members 17. At the ends of the cross-members 17 are secured two insulating operating rods 18 extending longitudinally on opposite sides of each arc-extinguishing assemblage 11. The operating rods 18 are pivotally connected at 19 to crank arms 20 which serve to rotate shafts 21 extending through the arc-extinguishing units 12.

Referring more particularly to Fig. 2 it will be observed that the shaft 21 has a squared portion 22 which rotatably supports a bridging contact 23 which electrically interconnects two stationary contacts 24 and 25. The stationary contacts 24 and 25 are resiliently pivotally supported on pins 26, the latter being supported by the end insulating plates 27, 28 of the arc-extinguishing unit 12.

Insulating means 29, in this instance comprising two circular plates 30, 31 are secured to and rotatable with the bridging contact 23. The insulating means 29 has formed thereon a plurality of surface irregularities 32, 33. More specifically, the surface irregularities 32, 33 are in this instance formed by notching the two plates 30, 31.

These notches serve to bring fresh liquid in contact with the arc as the bridging contact 23 is rotated, thus aiding the arc-extinguishing ac-

tion. Also the surface irregularities increase the creepage distance along the edge of the insulating means 23 immediately adjacent to the arc.

The plate structure for the arc-extinguishing unit 12 will now be described. The insulating plates forming the interrupting structure for the arc-extinguishing unit 12 are of four different types. The first type has a configuration such that it may be used to support a pin 26 and a leaf spring contact 34 secured in place by a terminal stud 35. The end insulating plates 27, 28 are of the first type. The second type merely have apertures 36 extending therethrough through which the stationary contacts 24, 25 partially extend. The insulating plates 37, 38 are of the second type.

The third type has a configuration more clearly shown in Fig. 4, the insulating plate shown being designated by the reference numeral 39. The insulating plate 39 has four apertures 40 extending therethrough through which insulating tie rods 41 pass, cooperating with nuts 42 and sleeves 43 to maintain the several plates and the arc-extinguishing units 12 comprising an assemblage 11 fixedly in place.

The insulating plate 39 has an enlarged portion 44 removed therefrom and a grooved portion 45 also formed therein, the purpose for which will appear more clearly hereinafter.

Immediately above the insulating plate 39 is an insulating plate 46 of the fourth type. The plate 46 has a configuration more clearly shown in Fig. 5. The plate 46 has an enlarged portion 47 removed therefrom and a grooved portion 48 formed therein, the purpose for which will appear more clearly hereinafter. Above the insulating plate 46 the plates 39, 46 alternately repeat to the upper insulating plate 37.

It will be observed from an inspection of Figs. 2 and 3 that upon the assembling of the several plates 39, 46 a pressure chamber, generally designated by the reference numeral 49, is formed adjacent the contacts 25, 50 which cooperate to establish a pressure-generating arc indicated by the dotted line 52 in Fig. 2. The pressure created at the pressure-generating arc 52 forces fluid, in this instance oil, to flow toward the interrupting arc 53 through a plurality, in this instance four, pairs of inlet passages, each of which is designated by the reference numeral 54. The inlet passages 54 are formed by the grooved portions 45 formed in the plates 39.

The interrupting arc 53 is established between the stationary contact 24 and the movable contact 55 within an interrupting passage generally designated by the reference numeral 56. Fluid may exhaust out of the interrupting passage 56 through a plurality of, in this instance three, pairs of vent passages, each of which is designated by the reference numeral 57. The vent passages 57 are formed by the grooved portion 48 formed in the insulating plates 46.

It will be observed that intermediate each inlet passage 54 and each vent passage 57 is an insulating portion (58 of plates 39, and 59 of plates 46) which cooperate with the surface irregularities 32 to establish a plurality of orifices, through which the interrupting arc 53 is drawn. Thus an orifice is formed between adjacently disposed inlet and vent passages. It will be observed that the vent passages 57 are positioned in pairs and the two vent passages 57 associated with each pair lead in substantially opposite directions out of the unit 12 on the lateral sides thereof.

The operation of the interrupter will now be ex-

plained. In the closed-circuit position of the interrupter, not shown, the electrical circuit therethrough comprises terminal stud 8, contact foot 10, conductor 60, terminal stud 61, leaf spring contact 34, stationary contact 24, movable contact 55, bridging contact 23, movable contact 50, stationary contact 25, leaf spring contact 34, terminal stud 35, conductor 63 to terminal stud 61 through the lower arc-extinguishing unit 12 in an identical manner to the terminal stud 35 of the lower arc-extinguishing unit 12. The circuit then passes through a conductor 64 to the disconnect fingers 16 and thence through the bridging member 13 and through the left-hand arc-extinguishing assemblage 11 in an identical manner to the left-hand terminal stud 7.

When it is desired to open the electrical circuit passing through the interrupter, or in response to overload conditions in the circuit controlled by the interrupter, suitable operating mechanism, not shown, is actuated to cause downward movement of the operating rod 14. The downward movement of the operating rod 14 causes downward movement of the ends 15 of the bridging member 13 to permit downward movement of the cross-members 17 and insulating operating rods 18.

Considering only the right-hand arc-extinguishing assemblage 11, it will be observed that opening or downward movement of the rods 18 will cause counterclockwise rotation of the shafts 21. The rotation of the shaft 21 will also cause a counterclockwise rotation of the bridging contact 23 to effect a simultaneous separation between the movable contacts 50, 55 and the stationary contacts 24, 25. The result is a simultaneous establishing of a pressure-generating arc 52 and an interrupting arc 53 within the arc-extinguishing unit 12. The pressure-generating arc 52 established within the pressure chamber 49 generates pressure therein which forces oil to pass through the inlet passages 54 into the interrupting passage 56 toward the interrupting arc 53. The oil strikes the interrupting arc 53 and passes through orifices defined by the portions 58, 59 and the surface irregularities 32 to exhaust out of the interrupting passage 56 through the several vent passages 57.

It will, from the foregoing description, be apparent that the interrupting arc 53 is subjected to fresh streams of oil under pressure striking it at a plurality of points along its length. Also fluid which has contacted the interrupting arc 53 is permitted to exhaust out of the interrupting passage 56 at a plurality of intermediate points along the length of the arc 53. The result is a rapid extinction of the interrupting arc 53, and a consequent breaking of the electrical circuit passing through the interrupter.

When the movable contacts 59, 55 strike the plates 37, 38, respectively, the downward movement of the rods 18 is halted and the ends 15 of bridging member 13 separate from the disconnect fingers 16 to introduce two isolating gaps into the circuit. Fresh oil may then flow into the units 12 through the several vent passages 57 as the residual gases escape through the check valve 68. During the closing operation the upward movement of the bridging member 13 causes the ends 15 thereof to strike the cross-members 17 thereby effecting an upward movement of the rods 18. The upward movement of the rods 18 effects a suitable rotation of the shafts 21 and the bridging contacts 23 to cause a re-engagement between the stationary contacts 24, 25 and

movable contacts 50, 55 to effect a completion of the electrical circuit through the interrupter.

Certain features of the interrupting structure comprising the inlet passages 54 and the vent passages 57 are disclosed and claimed in United States patent application Serial No. 465,244, filed November 11, 1942, by Leon R. Ludwig, Winthrop M. Leeds and Benjamin P. Baker, now U. S. Patent 2,406,469, issued August 27, 1946, and assigned to the assignee of the instant application.

Figs. 6 through 10 show a modified type of arc-extinguishing assemblage 11 comprising modified types of arc-extinguishing units generally designated by the reference numeral 65. The modified type of arc-extinguishing unit 65 is generally similar in construction to the construction of the unit 12 previously described with the exception that the vent passages 66 formed in the modified vent plates 67 (Fig. 9) extend out the end of the unit 65. This arrangement tends to bias the arc outwardly against the orifice edges 58 and 59 which act as arc splitters. Other features of the unit 65 are identical in construction to the features previously described in connection with the arc-extinguishing unit 12; consequently, a minute description thereof is deemed unnecessary.

From the foregoing description it will be apparent that I have provided an improved circuit interrupter in which the interrupting structure is of novel construction. Tests have clearly shown that the interrupting structure described above with its multi-orifice arrangement has been found to give highly effective arc interrupting action at current zero and yet to disturb the interrupting arc 53 less at the current peak than straight cross blast devices, thus giving very low arc energy. It will also be observed that in the foregoing construction by having the portions 58, 59 cooperate with the surface irregularities 32 to form the orifices between adjacent inlet and vent passages the resulting construction is more compact than the commercial device embodying the interrupting structure and disclosed in the aforesaid patent by Leon R. Ludwig, Winthrop M. Leeds and Benjamin P. Baker.

Although I have shown and described specific structures, it is to be clearly understood that the same were merely for the purpose of illustration and that changes and modifications may readily be made therein by those skilled in the art without departing from the spirit and scope of the appended claims.

I claim as my invention:

1. In a circuit interrupter, an arc-extinguishing unit, two relatively stationary contacts associated with the unit and disposed adjacent the end portions thereof, a bridging contact for electrically interconnecting the two stationary contacts in the closed circuit position, means pivotally mounting the bridging contact intermediate the ends thereof entirely within the unit, a pressure chamber disposed within the unit, the bridging contact being separable from one of the stationary contacts to establish a pressure-generating arc within the pressure chamber, an interrupting passage disposed within the unit, the bridging contact being separable from the other stationary contact to establish an interrupting arc within the interrupting passage, and a plurality of inlet passages leading from the pressure chamber into the interrupting passage to permit fluid to flow toward the interrupting arc.

2. In a circuit interrupter, an arc-extinguishing unit, two relatively stationary contacts as-

sociated with the unit and disposed adjacent the opposite ends thereof, a bridging contact positioned entirely within the unit for electrically interconnecting the two stationary contacts in the closed circuit position, a pressure chamber disposed within the unit, means pivotally mounting the bridging contact intermediate the ends thereof, the bridging contact being separable from one of the stationary contacts to establish a pressure-generating arc within the pressure chamber, an interrupting passage disposed within the unit, the bridging contact being separable from the other stationary contact to establish an interrupting arc within the interrupting passage, a plurality of inlet passages leading from the pressure chamber into the interrupting passage to permit fluid to flow toward the interrupting arc, and a plurality of vent passages leading away from the interrupting passage to permit the exhausting of fluid therefrom.

3. In a circuit interrupter, an arc-extinguishing unit, two relatively stationary contacts associated with the unit and positioned adjacent the opposite ends thereof, a bridging contact for electrically interconnecting the two stationary contacts in the closed circuit position and disposed wholly within the unit, a pressure chamber disposed within the unit along one side thereof, the bridging contact being separable from one of the stationary contacts to establish a pressure-generating arc within the pressure chamber, an interrupting passage disposed within the unit along the other side thereof, the bridging contact being separable from the other stationary contact to establish an interrupting arc within the interrupting passage, a plurality of inlet passages leading from the pressure chamber into the interrupting passage on both sides of the bridging contact to permit fluid to flow toward the interrupting arc, means pivotally mounting the bridging contact intermediate the ends thereof entirely within the unit, and means for effecting the rotation of the bridging contact wholly within the unit during the opening and closing operations of the interrupter.

4. In a circuit interrupter, an arc-extinguishing unit, two relatively stationary contacts associated with the unit and disposed adjacent the opposite ends thereof, a bridging contact for electrically interconnecting the two stationary contacts in the closed circuit position and positioned wholly within the unit, a pressure chamber disposed within the unit along one side thereof, the bridging contact being separable from one of the stationary contacts to establish a pressure-generating arc within the pressure chamber, an interrupting passage disposed within the unit along the other side thereof, the bridging contact being separable from the other stationary contact to establish an interrupting arc within the interrupting passage, a plurality of inlet passages straddling the bridging contact and leading from the pressure chamber into the interrupting passage to permit fluid to flow toward the interrupting arc at different levels, a plurality of vent passages leading away from the interrupting passage at intermediate levels to permit the exhausting of fluid therefrom, means pivotally mounting the bridging contact intermediate the ends thereof within the unit, and means for effecting the rotation of the bridging contact during the opening and closing operations of the interrupter.

5. In a circuit interrupter, an arc-extinguishing unit, two relatively stationary contacts associated with the unit and disposed adjacent the

opposite ends thereof, a bridging contact positioned wholly within the unit for electrically interconnecting the two stationary contacts in the closed circuit position, a pressure chamber disposed within the unit along one side thereof, the bridging contact being separable from one of the stationary contacts to establish a pressure-generating arc within the pressure chamber, an interrupting passage disposed within the unit along the other side thereof, the bridging contact being separable from the other stationary contact to establish an interrupting arc within the interrupting passage, a plurality of inlet passages on both sides of the bridging contact and leading from the pressure chamber into the interrupting passage to permit fluid to flow toward the interrupting arc, means pivotally mounting the bridging contact intermediate the ends thereof within the unit, means for effecting the rotation of the bridging contact during the opening and closing operations of the interrupter, and insulating means carried by and rotatable with the bridging contact for confining at least one of the arcs.

6. In a circuit interrupter, an arc-extinguishing unit, two relatively stationary contacts associated with the unit and disposed adjacent the opposite ends thereof, a bridging contact positioned wholly within the unit for electrically interconnecting the two stationary contacts in the closed circuit position, a pressure chamber disposed within the unit along one side thereof, the bridging contact being separable from one of the stationary contacts to establish a pressure-generating arc within the pressure chamber, an interrupting passage disposed within the unit along the other side thereof, the bridging contact being separable from the other stationary contact to establish an interrupting arc within the interrupting passage, a plurality of inlet passages straddling the bridging contact and leading from the pressure chamber into the interrupting passage to permit fluid to flow toward the interrupting arc, means pivotally mounting the bridging contact intermediate the ends thereof within the unit, means for effecting the rotation of the bridging contact during the opening and closing operations of the interrupter, and insulating means carried by and rotatable with the bridging contact, the insulating means having surface irregularities formed thereon for confining at least one of the arcs.

7. In a circuit interrupter, an arc-extinguishing unit, two relatively stationary contacts associated with the unit and positioned adjacent the opposite ends thereof, a bridging contact disposed wholly within the unit for electrically interconnecting the two stationary contacts in the closed circuit position, a pressure chamber disposed within the unit along one side thereof, the bridging contact being separable from one of the stationary contacts to establish a pressure-generating arc within the pressure chamber, an interrupting passage disposed within the unit along the other side thereof, the bridging contact being separable from the other stationary contact to establish an interrupting arc within the interrupting passage, a plurality of inlet passages leading from the pressure chamber into the interrupting passage at certain levels to permit fluid to flow toward the interrupting arc, a plurality of vent passages leading away from the interrupting passage at intermediate levels to permit the exhausting of fluid therefrom, means pivotally mounting the bridging contact intermediate the ends thereof wholly within the unit, means for

effecting the rotation of the bridging contact during the opening and closing operations of the interrupter, insulating means carried by and rotatable with the bridging contact for confining at least one of the arcs, and the insulating means having surface irregularities formed thereon.

5 8. In a circuit interrupter, an arc-extinguishing unit, two relatively stationary contacts associated with the unit and disposed adjacent the opposite ends thereof, a bridging contact disposed wholly within the unit for electrically interconnecting the two stationary contacts in the closed circuit position, a pressure chamber disposed within the unit, the bridging contact being separable from one of the stationary contacts to establish a pressure-generating arc within the pressure chamber, an interrupting passage disposed within the unit, the bridging contact being separable from the other stationary contact to establish an interrupting arc within the interrupting passage, a plurality of inlet passages leading from the pressure chamber into the interrupting passage to permit fluid to flow toward the interrupting arc, a plurality of vent passages leading away from the interrupting passage to permit the exhausting of fluid therefrom, means pivotally mounting the bridging contact within the arc extinguishing unit intermediate the ends thereof, means for effecting the rotation of the bridging contact during the opening and closing operations of the interrupter, insulating means carried by and rotatable with the bridging contact, the insulating means having surface irregularities formed thereon, and insulating means disposed along the interrupting passage having surface irregularities which cooperate with the irregularities formed on the insulating means rotatable with the bridging contact to provide a plurality of orifices through which the interrupting arc is drawn.

30 9. In a circuit interrupter, an arc-extinguishing unit, two relatively stationary contacts associated with the unit and disposed adjacent the opposite ends thereof, a bridging contact for electrically interconnecting the two stationary contacts in the closed circuit position, a pressure chamber disposed within the unit, the bridging contact being separable from one of the stationary contacts to establish a pressure-generating arc within the pressure chamber, an interrupting passage disposed within the unit, the bridging contact being separable from the other stationary contact to establish an interrupting arc within the interrupting passage, a plurality of inlet passages leading from the pressure chamber into the interrupting passage to permit fluid to flow toward the interrupting arc, a plurality of vent passages leading away from the interrupting passage to permit the exhausting of fluid therefrom, means pivotally mounting the bridging contact intermediate the ends thereof wholly within the unit, means for effecting the rotation of the bridging contact during the opening and closing operations of the interrupter, insulating means carried by and rotatable with the bridging contact, the insulating means having surface irregularities formed thereon, and insulating means disposed along the interrupting passage having surface irregularities which cooperate with the irregularities formed on the insulating means rotatable with the bridging contact to provide a plurality of orifices through which the interrupting arc is drawn, an orifice being formed between adjacently disposed inlet and vent passages.

10. In a circuit interrupter, a stationary contact, a movable contact, means for pivotally mounting the movable contact, means effecting the rotation of the movable contact during the opening and closing operations of the interrupter, an interrupting passage, the movable contact separating from the stationary contact to establish an interrupting arc within the interrupting passage, means forming a plurality of inlet passages leading toward the interrupting passage at certain levels, means forming a plurality of vent passages leading from the interrupting passage at intermediate levels, and insulating means carried by and rotatable with the movable contact to confine the interrupting arc.

11. In a circuit interrupter, a stationary contact, a movable contact, means for pivotally mounting the movable contact, means effecting the rotation of the movable contact during the opening and closing operations of the interrupter, an interrupting passage, the movable contact separating from the stationary contact to establish an interrupting arc within the interrupting passage, means forming a plurality of inlet passages leading toward the interrupting passage at a plurality of levels, means forming a plurality of vent passages leading from the interrupting passage at a plurality of intermediate levels, and insulating means carried by and rotatable with the movable contact to confine the interrupting arc, the insulating means having surface irregularities.

12. In a circuit interrupter, a stationary contact, a movable contact, means for pivotally mounting the movable contact, means effecting the rotation of the movable contact during the opening and closing operations of the interrupter, an interrupting passage, the movable contact separating from the stationary contact to establish an interrupting arc within the interrupting passage, means forming a plurality of inlet passages leading toward the interrupting passage at certain levels, means forming a plurality of vent passages leading from the interrupting passage at intermediate levels, insulating means carried by and rotatable with the movable contact to confine the interrupting arc, the insulating means having surface irregularities, and the interrupting passage being formed with a plurality of surface irregularities which cooperate with the aforementioned surface irregularities to provide a plurality of orifices through which the interrupting arc is drawn.

13. In a circuit interrupter, a stationary contact, a movable contact, means for pivotally mounting the movable contact, means effecting the rotation of the movable contact during the opening and closing operations of the interrupter, an interrupting passage, the movable contact separating from the stationary contact to establish an interrupting arc within the interrupting passage, means forming a plurality of inlet passages leading toward the interrupting passage at certain levels, means forming a plurality of vent passages leading from the interrupting passage at intermediate levels, insulating means carried by and rotatable with the movable contact to confine the interrupting arc, the insulating means having surface irregularities, the interrupting passage being formed with a plurality of surface irregularities which cooperate with the aforementioned surface irregularities to provide a plurality of orifices through which the interrupting arc is drawn, and an orifice being

formed between adjacently disposed inlet and vent passages.

14. In a circuit interrupter, an arc-extinguishing unit, two relatively stationary contacts associated with the unit and disposed adjacent the opposite ends thereof, a bridging contact disposed within the unit for electrically interconnecting the two stationary contacts in the closed circuit position, means pivotally mounting the bridging contact intermediate the ends thereof, a pressure chamber disposed within the unit, the bridging contact being separable from one of the stationary contacts to establish a pressure-generating arc within the pressure chamber, an interrupting passage disposed within the unit, the bridging contact being separable from the other stationary contact to establish an interrupting arc within the interrupting passage, a plurality of inlet passages leading from the pressure chamber into the interrupting passage at certain levels to permit fluid to flow toward the interrupting arc, a plurality of vent passages leading away from the interrupting passage at intermediate levels to permit the exhausting of fluid therefrom, and all the vent passages leading out one end of the unit.

15. In a circuit interrupter, an arc-extinguishing unit, two relatively stationary contacts associated with the unit and disposed adjacent the opposite ends thereof, a bridging contact disposed within the unit for electrically interconnecting the two stationary contacts in the closed circuit position, means pivotally mounting the bridging contact intermediate the ends thereof within the unit, a pressure chamber disposed within the unit, the bridging contact being separable from one of the stationary contacts to establish a pressure-generating arc within the pressure chamber, an interrupting passage disposed within the unit, the bridging contact being separable from the other stationary contact to establish an interrupting arc within the interrupting passage, a plurality of inlet passages leading from the pressure chamber into the interrupting passage at a plurality of levels to permit fluid to flow toward the interrupting arc, a plurality of vent passages leading away from the interrupting passage at a plurality of intermediate levels to permit the exhausting of fluid therefrom, the vent passages being positioned in pairs, and the two vent passages associated with a pair leading in substantially opposite directions out of the unit on the lateral sides thereof.

16. In a circuit interrupter of the liquid break type, an arc extinguishing unit, two relatively stationary contacts disposed adjacent the end portions of the unit, a bridging contact disposed interiorly of the unit for electrically interconnecting the two stationary contacts in the closed circuit position, means pivotally mounting the bridging contact intermediate the ends thereof within the arc extinguishing unit, and a substantially circular plate member composed of insulating material secured to and rotatable with the bridging contact.

17. In a circuit interrupter of the liquid break type, means including a plurality of contiguously disposed insulating plates for forming an arc extinguishing unit, a pair of relatively stationary contacts disposed at opposed ends of the unit, some of the plates having openings formed therein to provide a pressure-generating chamber laterally along one side of the unit interiorly thereof, some of the plates having openings therein for forming an interrupting chamber

11

extending laterally along one side of the unit interiorly thereof, a bridging contact disposed entirely within the unit for electrically interconnecting the two stationary contacts in the closed circuit position, means pivotally mounting the bridging contact intermediate the ends thereof wholly within the unit, the bridging contact being separable from one of the stationary contacts to establish a pressure-generating arc within the pressure-generating chamber, the bridging contact also being separable from the other stationary contact to establish an interrupting arc within the interrupting chamber, and a substantially circular plate member fixed to and rotatable with the bridging contact.

18. The combination in a circuit interrupter having a rotatable bridging contact electrically interconnecting two relatively stationary contacts, of an arc extinguishing unit including a plurality of contiguously disposed insulating plates, the stationary contacts being disposed at opposite ends of the unit, the bridging contact being disposed wholly within the unit, means pivotally mounting the bridging contact intermediate the ends thereof within the unit, some of the plates having openings formed therein to provide a pressure-generating chamber disposed interiorly within the unit along one side thereof, some of the plates having openings therein which upon alignment form an interrupting chamber extending along the other side of the arc extinguishing unit, the bridging contact being separable from one stationary contact to estab-

12

lish a pressure-generating arc within the pressure-generating chamber, and the bridging contact also being separable from the other stationary contact to establish an interrupting arc within the interrupting chamber.

19. In a circuit interrupter of the liquid break type, an arc extinguishing unit, two relatively stationary contacts associated with the unit and disposed adjacent the end portions thereof, a bridging contact for electrically interconnecting the two stationary contacts in the closed circuit position and disposed wholly within the unit, means pivotally mounting the bridging contact intermediate the ends thereof entirely within the unit, means defining a pressure-generating chamber disposed laterally along one side of the unit interiorly thereof, means defining an interrupting chamber disposed laterally along the other side of the unit interiorly thereof, and a plurality of separate passages interconnecting the pressure-generating chamber with the interrupting chamber.

WINTHROP M. LEEDS.
